CLAIM

The ornamental design for an insulating tall cup with lid, as shown and described.

DESCRIPTION

FIG. 1 is a front perspective view of my new design for an insulating tall cup with a lid;

FIG. 2 is an exploded view thereof;

FIG. 3 is bottom perspective view thereof;

FIG. 4 is a right view thereof;

FIG. 5 is a back view thereof;

FIG. 6 is a front view thereof;

FIG. 7 is a top view thereof;

FIG. 8 is a bottom view thereof; and,

FIG. 9 is a bottom perspective view of my new design with a cup portion removed for clarity of disclosure.

The portions of the insulating cup with lid shown in broken line form no part of the claimed design.
